Des. 214,196
Patented May 20, 1969

214,196

UTILITY VACUUM CLEANER OR SIMILAR ARTICLE

Clyde H. Williams, Coldwater, Mich., assignor to The
Scott & Fetzer Company, Bronson, Mich., a corpora-
tion of Ohio

Filed Sept. 11, 1968, Ser. No. 13,490

Term of patent 14 years

Int. Cl. D15—07

U.S. Cl. D49—11

FIG. 4

FIG. 3

FIGURE 1 is a top plan view of the utility vacuum cleaner embodying my new design;

FIGURE 2 is a side elevational view thereof;

FIGURE 3 is a side elevational view illustrating the utility vacuum cleaner rotated 90° from the view shown in FIGURE 2;

FIGURE 4 is a bottom plan view thereof; and

FIGURE 5 is a fragmentary cross-sectional view illustrating the new design embodied in the bottom portion of the utility vacuum cleaner.

I claim:

The ornamental design for a utility vacuum cleaner or similar article, as shown.
